Inventor

By *Richard B. Oliver.*

Attorney

UNITED STATES PATENT OFFICE.

JOHN D. MACLACHLAN, OF CHADWICK, MISSOURI,

ENGINE.

Application filed September 7, 1921, Serial No. 499,050. Renewed August 4, 1923.

To all whom it may concern:

Be it known that I, JOHN D. MACLACHLAN, a citizen of the United States, residing at Chadwick, in the county of Christian 5 and State of Missouri, have invented certain new and useful Improvements in Engines, of which the following is a specification.

This invention relates to new and useful 10 improvements in engines of the two cycle type, the primary object of the invention being to utilize the force spent on the cylinder head for thoroughly compressing the combustible charge admitted into the cylinder.

Another object of the invention is to provide a device of the above character including a piston having about one-third the displacement of an ordinary piston whereby 20 a smaller amount of fuel is used to run the engine without sacrificing power produced by the reduction of the charge.

A further object of the invention is to provide an engine embodying a pair of opposed pistons having connection with a common crank shaft with the result of a quicker exhaust of the spent gases.

A still further object of the invention is to provide an engine having a crank throw 30 approximately one-half that of the pistons whereby it is possible to obtain a long stroke motor with a small bore cylinder.

Still another object of the invention is to provide an arrangement whereby the spark 35 plug is covered except at the instant of ignition of the combustible charge thereby providing means for effectively preventing fouling of the plug.

Another object of the invention is to provide a piston within another piston and between which the combustible charge is compressed and whereby necessity of cooling 40 of the cylinder head is reduced to a minimum.

Other objects and advantages of the invention will become apparent during the course of the following description.

In the accompanying drawings forming a part of the specification and wherein like 50 numerals are employed to designate like parts throughout the several views.

Figure 1 is a vertical section through the engine illustrating the position of the various parts at the end of the exhaust stroke.

Figure 2 is a similar view taken longitudinally of the crank shaft illustrating

the positions of the various parts at the end of the compression strokes.

Figure 3 is a top plan of the crank case.

Figure 4 is a vertical section through one 60 of the connecting rod pockets, and

Figure 5 is a section of the means for connecting the connecting rods to one of the pistons.

In the drawings wherein for the purpose 65 of illustration is shown the preferred embodiment of my invention, the numeral 6 designates a crank case which may be of any desired shape and has its top provided with a central opening 7 through which the 70 piston may pass, it being noted that openings 8 extend from diametrically opposite points of the opening to admit of connecting rods operating in the crank case. A crank shaft 9 is journaled through the 75 crank case in the ordinary manner and is equipped with three crank portions 10 within the crank case for a purpose which will presently appear.

A cylinder 11 having the usual piston 80 bore therethrough and a lower flanged end is bolted by means of bolts 12 to the top of the crank case as clearly seen. It will be noted that the bore through the cylinder extends entirely therethrough there being no 85 top or bottom to the cylinder for closing the bore, and furthermore only the sides of the cylinder are waterjacketed as at 13. The spark plug opening 14 extends transversely through the cylinder wall as shown as do 90 the carburetor inlets 15 and exhaust outlets 16. As best seen in Figure 4 and Figure 2, the cylinder 11 is provided at diametrically opposite portions with the connecting rod pockets 17 extending longitudinally thereof 95 and up the side of the cylinder a substantial distance.

To the top of the cylinder is bolted a surge plunger casing or chamber 18 the interior of which if noted carefully in Figure 100 1 will be seen to be slightly larger in diameter than the bore through the cylinder, this being more noticeable at the right side of the figure where the live gas is adapted to enter the bypass openings 19 as clearly seen 105 in Figures 1 and 2. The top of the surge chamber 18 is provided with a central threaded opening adapted for the reception of a compression spring adjuster 20, the lower end of which is provided with a reduced 110 depending flange for reception in one end of the compression spring 21 located in

the surge plunger chamber 22. The other end of the compression spring is adapted to encircle a central enlargement formed upon a surge plunger 23 which is provided with 5 peripheral packing rings to establish a working fit between the plunger and the walls of the chamber.

The interior of the compression spring adjuster is screw threaded to receive a depending tubular threaded stem 24 of a breather cap 25, the latter being semi-circular to thoroughly cover air openings 26 in the upper end of the tubular stem 24. Lock nuts 27 are associated with both the tubular stem 10 24 and the adjuster 20 so that these two elements may be locked in the desired position. In case it is desired to vary the amount of air entering and exhausting from the surge chamber, the breather cap is simply adjusted 15 so as to vary the sizes of the opening 26 in the tubular stem. For the purpose of lubricating the surge plunger, an opening is provided in top of the surge casing for the admission thereinto of lubricants and this 20 opening is normally closed by its threaded plug 28 as clearly seen.

Referring more particularly to Figures 1 and 2, it will be noted that the by-passes 19 are provided with inlets and outlets, the uppermost openings being inlets and exposed so as to open into both the bore and the top portion of the cylinder 11. The lowermost openings 19 indicate the by-pass outlets and are disposed slightly below the inlets.

35 An elongated cylinder shaped piston 29 is adapted to slide upon the walls of the bore through the cylinder 11 and has a closed top 30 and open bottom. If desired, the exterior surface of the top 30 may be provided 40 with a heat conducting plate so as to cause rapid vaporization of the fuel admitted into the cylinder. The upper end of the cylinder piston 29 has its side wall equipped with a plurality of inlet openings 31, the number 45 of which correspond to the same number of by-passes 19. By the provision of these inlet openings, a charge may be admitted into the upper end of the cylinder piston 29 which forms the combustion chamber of the 50 engine. Directly below the openings 31, the bore of the cylinder piston is slightly enlarged so that an annular shoulder 32 is provided upon the interior of the piston.

The wall of the cylinder piston 29 opposite 55 the wall in which the inlet openings 31 are provided, is equipped with an exhaust opening 33 which correspond to the exhaust opening communicating with the exhaust port 16 in the cylinder. It will be noted 60 that the length of the cylinder piston is approximately the same as the length of the cylinder and is grooved at intervals, to receive oil whereby the walls of the cylinder may be effectively lubricated.

65 The walls of the cylinder piston are pro-

vided at diametrically opposite points with a pair of laterally extending pintles 34 as best seen in Figures 2 and 5, and upon these pintles hardened steel sleeves 36 are pressed and upon which fit the bushings 37 of connecting rods 38. It will be noted that the lower ends of the connecting rods 38 are connected to the outermost cranks 10 of the shaft 9 and in order to prevent displacement of the connecting rods and steel sleeves from the pintles, a disk 39 having a central aperture therein is adapted to be clamped upon the outer ends of the pintle by means of screws 41 having relatively broad heads and the shanks of which enter central threaded openings extending longitudinally of the pintles 34. To prevent the screws 41 from turning, auxiliary screws 42 are threaded through the heads of the screws 41 and into the pintles. The ends of the connecting rods which are fastened to the pintles are bifurcated as at 43, a set screw 44 being provided to securely clamp the connecting rods to the pintles.

A piston 35 of the ordinary construction 90 is adapted to slide within the cylinder piston 29 from its lower end up to the shoulder 32 therein. A wrist pin 46 journaled in the piston forms a connection with a connecting rod 47, the lower end of which is associated 95 with the intermediate crank 10 of the shaft 9. Having fully described the various parts of the invention, the operation of the same is as follows: First, it will be understood that while the cylinder piston 29 is moving upwardly to compress the charge, the piston 35 is moving downwardly to exhaust the 100 spent gases.

As the cylinder piston 29 uncovers the carburetor inlet 15, the combustible mixture is 105 drawn into the upper end of the cylinder 11 and comes in contact with the surge plunger 23. About the time that this surge plunger is about to rise by compression of the fresh 110 charge, the exhaust port 16 opens and as the pressure in the cylinder piston is reduced by the time the by-pass 19 opens. After the surge plunger is raised the gas mixture quickly passes down in the cylinder piston with the added force of the surge-plunger returning to its normal position and 115 incidentally forcing all burned gases ahead of it out through the exhaust. It will of course be understood that upon the compression stroke of the cylinder piston 29, the 120 first charge will be compressed between the top of the cylinder piston and the surge plunger 23. As the pressure of the gases increases, the surge-plunger will be moved upwardly into its chamber to make room for the compressed new charge so that when the top of the cylinder piston reaches and covers the uppermost inlet of the by-pass 19, the 125 ports 31 of the cylinder piston will register with the outlet openings of the by-pass 19 130

so that the compressed charge gas in the surge-chamber may be forced by the surge-plunger down through the by-passes into the upper end of the cylinder piston. During 5 this operation, the piston 35 will have covered the exhaust portion 33 and will be traveling upwardly of the cylinder 11 while the cylinder piston 29 is moving downwardly thereof whereby the charge of combustible 10 mixture will be compressed to the highest degree in the upper part of the cylinder piston. The charge is adapted to be fully compressed and ready for ignition as soon as the piston 35 reaches the shoulder 52 on the 15 interior of the cylinder piston and the space between the tops of the two pistons is arranged opposite the spark plug positioned in the opening 14. At this time, the timing mechanism will send a spark to the plug to 20 ignite the charge the explosion of which will force the two pistons in opposite directions to again begin the same cycle of operations as outlined above.

The foregoing description and accompanying drawings have reference to what might be considered to be the approved or preferred form of my invention. I desire it to be understood that I may make such changes in the construction and combination and arrangement of parts material, dimensions, etc., as may prove expedient and fall within the scope of the appended claims.

Having thus fully described my invention what I claim as new and desire to secure by 25 Letters Patent is:

1. An engine comprising a cylinder, a surge-plunger chamber associated therewith

and having a member adjustably associated with said chamber, a surge-plunger adapted for operation in said chamber, a compression spring associated with the plunger and said member, and a breather cap adjustably associated with said member for varying the amount of air entering the surge plunger chamber.

2. In a two cycle internal combustion engine, a crank case, a cylinder carried by the crank case, a crank shaft including a plurality of throws journaled in the crank shaft, a cylinder piston operable within the cylinder, a second piston operable within the cylinder piston for compressing a charge therein, means for connecting the second piston with one throw of the crank shaft, means connecting the cylinder piston with the other 55 throws of the crank shaft, an intake port formed in the cylinder, an exhaust port formed in the cylinder, an exhaust port formed in the cylinder piston adjacent to the lower end thereof, an intake port formed 60 in the cylinder piston adjacent to the upper end thereof, a by-path formed in the cylinder adjacent to the upper end thereof, an enlarged chamber formed in the upper end of the cylinder communicating with the upper end of the by-path, and a surge plunger reciprocably mounted in the enlarged portion of the chamber.

In testimony whereof I affix my signature in presence of two witnesses.

JOHN D. MACLACHLAN.
